Claims priority, application Japan Mar. 5, 1971

Term of patent 14 years

Int. Cl. D14—03
U.S. Cl. D56—4 D

FIG. 1

FIG. 2

FIG. 3

FIG. 4

FIG. 1 is a top, front and right side perspective view of a television receiver or similar article showing our new design;

FIG. 2 is a top plan view;

FIG. 3 is a left side elevational view; and

FIG. 4 is a rear, bottom and right side perspective view.

This application is a continuation of design application Ser. No. 177,542, filed Sept. 2, 1971, and now abandoned.

We claim:

The ornamental design for a television receiver or similar article, substantially as shown and described.
